UNITED STATES PATENT OFFICE.

JAY M. JOHNSON, OF CHICAGO, ILLINOIS.

COMMUTATION OR MULTIPLE-RIDE TICKET COLLECTOR.

1,145,313.

Specification of Letters Patent.

Patented July 6, 1915.

Application filed December 18, 1911. Serial No. 666,387.

To all whom it may concern:

Be it known that I, JAY M. JOHNSON, a citizen of the United States, and a resident of the city of Chicago, in the county of Cook and State of Illinois, have invented certain new and useful Improvements in Commutation or Multiple-Ride Ticket Collectors; and I do hereby declare that the following is a full, clear, and exact description of the same, reference being had to the accompanying drawings, and to the numbers of reference marked thereon, which form a part of this specification.

The object of this invention is to afford a cutting and collecting mechanism for tickets, whereby the single ride ticket cut from a commutation multiple ride ticket or transfer ticket, is collected and preserved for inspection of the accounting officers and are turned in at the same time cash fares are turned in.

It is also an object of the invention to afford a ticket register in connection with such a ticket collecting mechanism whereby the number of rides on such tickets will be clearly indicated and must coincide with the number of such tickets delivered to the accounting officers at the end of the run.

The invention is shown in connection with a street railway fare box and register such as set forth in my application for Letters Patent filed Nov. 7, 1910, Serial 591,093.

The invention in its preferred form, is hereinafter more fully described.

In said drawings: Figure 1 is a front elevation of a street railway fare register and box equipped with a ticket clipping and registering mechanism embodying my invention. Fig. 2 is a section on line 2—2 of Fig. 1. Fig. 3 is a side elevation of a device embodying my invention, with the operating lever broken away. Fig. 4 is a similar side elevation with one wall of the casing and the operating lever removed. Fig. 5 is a section on line 5—5 of Fig. 4. Fig. 6 is a section on line 6—6 of Fig. 5. Fig. 7 is a section taken on line 7—7 of Fig. 5. Fig. 8 is a top plan view of the ticket collector and register, showing the same removed from the fare box. Fig. 9 is a face view of a ticket adapted for use in connection with a ticket collector and register embodying my invention.

As shown in the drawings: 1, indicates the fare box, which may be, of course, of

any suitable kind, and which is provided in one side conveniently with a drawer 2, to receive the cash fares deposited, and in the opposite side thereof is provided with a drawer 3, to receive the tickets collected. 60 Extending through the top of the fare box at one side thereof, is a chute 4, of sufficient size to permit the collected tickets to fall therethrough to the drawer 3. Mounted upon the fare box in register with the chute is a 65 female die member 5, and, as shown, the back wall 6, of said female die member extends upwardly above the plane of said member, and affords a rear guide for the male die member 7. As shown, said female die member 70 at the back wall thereof, is constructed from sufficiently heavy stock to permit said back wall to be milled or otherwise shaped or formed to afford at each side thereof, forwardly projecting side walls 8, for the male 75 die member 7, and rigidly bolted thereto is a suitably shaped front guide wall, which may be milled or otherwise constructed to afford side walls integral therewith in a familiar manner so that when bolted together, the male die member is slidably supported between said front, rear and side walls, which serve as guides therefor, insuring precision of movement. Said male die member 7, is provided near its upper end 80 with a horizontal slot extending from the front side thereinto, and a recess concentric therewith on each side thereof, and a crank 10, provided with a crank shaft 11, therein, is journaled between the side guide walls, 85 as shown in Figs. 4 and 6, with said crank extending into said slot in the male die member, and a cover plate 12, is recessed into the face of said male die member to cover said slot, as shown in Fig. 7. A lever 13, is 90 rigidly engaged on one end of said shaft 10, for manual actuation, to operate said male die member in cutting the tickets, and secured on the opposite end of said shaft, is a longitudinally slotted crank arm 14, in 95 which is engaged a pin 15, secured on a lever 16, rigidly engaged on the shaft 17, of a register, which may be of the Veeder type, and which is actuated through the medium of any suitable ratchet and pawl in a familiar 100 manner by the actuation of said lever 16, by the crank shaft to register 1, on the veeder, with each full movement of the hand lever, and as shown, stops 18 and 19, 105 are provided on the veeder casing, limiting 110

the throw of the lever 16, to cause the veeder to register one with each actuation of said hand lever. A stop or gage 20, is provided on the female die member in alinement with 5 the side of the male die member, as shown in Fig. 6, to serve as a gage to limit the insertion of the ticket to a single ride space.

As shown, a leaf spring 21, is secured on the under side of the male die member 7, 10 with the free margin thereof directed downwardly and toward said gage 20, so that as the ticket is inserted into place between said die members, said leaf spring engaging thereon holds the same down upon the 15 female die member.

Secured on the crank shaft adjacent the operating lever 13, is a downwardly directed lever or arm 22, and engaged on the extremity of the arm by one of its ends, is a 20 torsion spring 23, which is coiled about said crank shaft and the other end thereof is engaged in continuous support, as, for instance, one of the guide walls for the male die member, said torsion spring being so 25 arranged and disposed to throw the die upwardly and the actuating lever to normal after each actuation of the die. The cutting faces of the die members may be constructed as preferred.

30 As shown, a metallic casing 24, incloses the cutter and veeder and all the operating parts thereof excepting the hand lever, and extends downwardly to near the lower end of the male die member, affording a tight 35 casing to preclude the operator interfering or tampering with the veeder or register. Said casing, as shown, is provided with a slot in the top thereof to permit the reading to be taken from said register as required. 40 Rigidly secured on said casing in position to limit the throw of said lever, is an inclined stop 25, and secured within the casing in position to engage the end of the lever 22, at the rearward limit of movement of said 45 hand lever, is a stop 26.

The operation is as follows: The ticket illustrated in Fig. 9, is provided with closely arranged, marginal portions adapted to be cut therefrom, and each appropriated to a single ride, or, if preferred, to a ride to a transfer point. The car bearing such tickets is received by the collector, is inserted beneath and into the die, to bring the edge thereof against the gage or stop 50 20, with the inner margin of the card bearing against the back guide wall for the male die member. When the lever 13, is actuated, the ride ticket is cut from said card and falls through said chute and into 55 60 the drawer in the fare box appropriated therefor. Each actuation of the lever 13, also actuates the veeder, which is directly connected with said crank shaft through the medium of the slotted arm 14. Such 65 actuation of the veeder, however, is limited

to sufficient movement to merely register one thereon.

At the end of the trip or run, the fares and tickets are removed from their respective drawers and the registers for each is 70 ready. Obviously, the number of tickets in said drawer must coincide with the number indicated by the register, as must the number of fares in the cash fare drawer coincide with the number indicated on its 75 register. In this manner reliable and certain check is kept upon the collector or conductor and dishonesty detected. Of course, it is to be understood that the ticket and the 80 cash fare drawers are provided with suitable locks 27, to prevent the collector or conductor having access to the contents of said drawers.

I am, of course, aware that details of the construction may be varied through a wide 85 range. However, I have described but a preferred form of my invention. I therefore do not purpose limiting the patent to be granted on this application otherwise than necessitated by the prior art. 90

I claim as my invention:

1. A device of the class described embracing a receptacle, a ticket cutter comprising fixed and movable dies mounted thereon to deliver thereinto, a crank shaft extending through one of said dies for operating the same, one of said dies slidable within the other, said fixed die affording a stop to limit the insertion of a ticket in one direction, and a stop secured on said fixed die 95 to limit the insertion of a ticket in another direction.

2. A device of the class described comprising a ticket cutter and collector to receive the cut tickets, male and female cutters, the former slidable in the latter to cut a ticket on only two edges, a crank shaft extending through the slidable cutter, and a handle connected thereto to actuate the same, stops for limiting the movement of 100 the ticket in two directions when inserted.

3. In a device of the class described a cutter adapted to cut single ride tickets from a multiple ride ticket, means for actuating said cutter and register simultaneously, and stops for limiting the insertion of the multiple ride ticket to permit only one single ride ticket to be cut therefrom at one time. 110

4. A device of the class described embracing the combination with a collecting fare box of a cutter associated therewith adapted to cut single trip tickets from multiple ride tickets, said cutter comprising male and female dies, integral guides extending upwardly from said female die adapted to guide said male die, a portion of said female die forming a stop limiting the insertion of the multiple ride ticket in one direction, means secured on said female 120 125 130

die to limit the insertion thereof in another direction, and manually operated means for actuating the cutter.

5. A device of the class described embodying a fare box, a receptacle therein for tickets, a manually operated male cutter, a female cutter affording upwardly extending guides for the former, said cutters mounted on the fare box and adapted to cut single 10 ride tickets from multiple ride tickets, means permitting the insertion of the multiple ride ticket from the front and side of

the device, means limiting the insertion thereof to one single ride ticket, and a chute delivering the cut tickets into said receptacle. 15

In testimony whereof I have hereunto subscribed my name in the presence of two subscribing witnesses.

JAY M. JOHNSON.
